UNITED STATES PATENT OFFICE.

GEORGE A. WOODMAN, OF CHICAGO, ILLINOIS, ASSIGNOR TO WOODMAN RAILWAY SUPPLY COMPANY, OF CHICAGO, ILLINOIS, A CORPORATION OF ILLINOIS.

CAR JOURNAL BOX.

Application filed September 10, 1926. Serial No. 134,588.

This invention relates to car journal boxes and its object is to prolong the life of the box by protecting it against wearing engagement with the pedestal jaws and the equalizer bar.

5 Other objects of the invention are to provide a journal box with a liner at each side thereof having a portion forming a liner or wear plate for the equalizer bar; to anchor the liner to the box; and to anchor the equalizer bar to the liner. And a further object is to 10 protect the top of the box against wear from the bearing wedge.

In the accompanying drawings I have illustrated the invention in selected embodiments 15 and referring thereto:

Fig. 1 is a side elevation of a journal box (without the lid) embodying the invention.

Fig. 2 is a front view of the box partly in section.

20 Fig. 3 is a perspective view of a liner for one half of the box.

Fig. 4 is a perspective view of a one-piece liner for both sides and the top of the box.

25 Fig. 5 is a detail perspective view showing another manner of anchoring the liner to the box.

Fig. 6 is a transverse sectional view of a box showing another embodiment of the wedge liner.

30 Fig. 7 is a detail perspective view showing another way of anchoring the outside liners to the box.

Fig. 8 is a detail perspective view of the wedge liner shown in Fig. 6.

35 Referring to the drawings 6 is the journal box having side ribs 7 and top ribs 8. The box may be of any construction to which my invention is or may be adapted, the drawing showing a commercial type of box with which 40 I propose to use the invention.

The single liner shown in Fig. 3 comprises a plate 9 having side flanges 10, a bottom hook projection 11, and an inclined arm 12 having a horizontal extension 13 provided with an anchor lug 14. When the liner is made in this form two are used on each box, one on each side of the box, and the two liners are made alike and are interchangeable one for the other. The liner plate fits between the side ribs 7—7 on the box, and the flanges 10—10 on the liner plate receive the jaw of the car truck pedestal. The upper portion of the liner plate is slotted downward from the upper end of the plate to form the arm 12 which is bent inwardly and provided with a horizon-

tal extension 13 having an end lug 14 to form an anchor for engagement with the recess 15 in the top of the box, the extension being recessed at 16 alongside of the lug. This construction permits two liner plates exactly 60 alike to be applied to the sides of the box with the anchor lugs engaged end to end in the recess 15, the lug of one liner plate being disposed in the recess 16 of the other liner plate. The upper portions 17 of the plate, 65 alongside the arm 12, project upward in the plane of the body of the plate to engage the pedestal jaw throughout the height of the box, or substantially so.

The arm 12 inclines across the recessed part 70 6' in the side of the box so that the extensions 13 on two liner plates together form a liner or wear plate on the top of the box to receive the equalizer bar 18. The lug 14 projects upward to engage a recess 19 in the equalizer 75 bar, as well as downward to engage the recess 15 in the top of the box, so that this lug constitutes an anchor for engaging the liner plate with the box and the equalizer bar with the liner plate and through the liner plate with 80 the box. After the liner has been arranged in place on the box the projection 11 is heated and bent upward into hook form to engage the bottom of the box whereby the liner is held in fixed position on the box by engagement of the anchor lug 14 and the hook 11 85 with the box. The liner or wear plate for the equalizer bar provided by the extensions 13 of two plates 9 prevents the equalizer bar from wearing the top of the box just as the 90 liner plates 9 prevent the pedestal jaws from wearing the sides of the box, and this forms a substantial and efficient protection for the box against wear from these parts and thereby prolongs the life of the box.

95 Since the single liner is interchangeable for use on either side of the box it may be desirable to embody the invention in this form, but I may make two single liners in one piece to form the double liner 20 shown 100 in Fig. 4. This double liner comprises two single liners joined together at the single anchor lug 21 which, it will be observed, is equivalent to the two anchor lugs on two single liners. I may also use two single liner plates for a box and weld them together to form a double liner substantially as shown in Fig. 4, and this may be done before or after the liner is applied to the box.

I may provide a side lug 22 on the equalizer 110

bar liner extension 13 to engage a recess like 23 in the top rib 8 on the box instead of providing a recess like 15 in the top of the box and forming the anchor lug to engage the 5 same.

I also prefer to provide an inside liner 24 (Fig. 6) for the top of the box to protect it against wear from the wedge 25. This liner may be secured to the top of the box by 10 rivets 26 or by welding or other suitable means; and the liner may have an anchor 27 projecting through an opening 28 in the top of the box and engaged by the equalizer bar. In this construction the extensions 13 on the 15 single liner (Fig. 7) would have side projections 29 engaging recesses 30 in the ribs 8 on the box.

I have provided a novel means of simple construction for protecting the top of the 20 box as well as the sides of the box against wear in service and thereby prolonging the life of the box and reducing the cost of maintenance. By making the liner in the forms 25 shown and described I simplify the means for protecting the box and enable the outside liner to be applied to the top as well as to the side of the box in one operation requiring only the bending of the hook 11 to secure the liner in permanent position on the box. 30 It may be desirable to change the form and construction of parts of the invention more or less to adapt it for different boxes and I reserve the right to make all such changes 35 as fairly fall within the scope of the following claims.

I claim:

1. A one-piece liner for journal boxes comprising a side plate to fit against a side of the 40 box for engagement with a pedestal jaw, said side plate being slotted downward from its top and the slotted part being inclined and forming an arm, and a horizontal extension on the upper end of said arm to fit against the top of the box and receive an equalizer bar.

2. A one-piece liner for journal boxes having a part thereof to fit against a side of the box for engagement with a pedestal jaw and a part thereof to fit against the top of the box and under an equalizer bar and receive 45 said equalizer bar, and a lug on the under 50 side of the latter part to make anchoring engagement with the box.

3. A one-piece liner for journal boxes having a part thereof to fit against a side of the box for engagement with a pedestal jaw and 55 a part thereof to fit against the top of the box and receive an equalizer bar, and a lug on the upper side of the latter part to make anchoring engagement with an equalizer bar.

4. A one-piece liner for journal boxes having a part thereof to fit against a side of the box for engagement with a pedestal jaw and a part thereof to fit against the top of the box and receive an equalizer bar, and a lug 60 on said latter part projecting downward to make anchoring engagement with the box and projecting upward to make anchoring engagement with an equalizer bar.

5. A one-piece liner for journal boxes having a part thereof to fit against a side of the 70 box for engagement with a pedestal jaw and a part thereof to fit against the top of the box and under an equalizer bar and receive 75 said equalizer bar, there being a lug at the top of the liner for engagement with the top of the box and a projection at the bottom 80 of the liner adapted to be bent to form a hook for engagement with the bottom of the box.

6. The combination of a journal box having a recess in the top thereof, of a liner 80 having a part to fit against a side of the box for engagement with a pedestal jaw and a part to fit against the top of the box and under an equalizer bar and receive said equalizer bar, a hook on the first part to engage 85 the bottom of the box, and a lug on the second part to engage said recess.

GEORGE A. WOODMAN.
